UNITED STATES PATENT OFFICE.

JAMES L. MCQUARRIE, OF MONTCLAIR, NEW JERSEY, ASSIGNOR TO WESTERN ELECTRIC COMPANY, OF NEW YORK, N. Y., A CORPORATION OF ILLINOIS.

CALLING DEVICE.

1,148,787.

Specification of Letters Patent. Patented Aug. 3, 1915.

Application filed March 10, 1915. Serial No. 13,454.

To all whom it may concern:

Be it known that I, JAMES L. MCQUARRIE, a citizen of the United States, residing at Montclair, in the county of Essex and State of New Jersey, have invented certain new and useful Improvements in Calling Devices, of which the following is a full, clear, concise, and exact description.

This invention relates to improvements in calling devices and more particularly to impulse senders for automatic and semi-automatic telephone systems.

In impulse senders of the above type, the impulses are usually sent out during the 10 turn movement of the dial. The user sends out impulses corresponding to digit numbers by inserting his finger in the proper holds and pulling the dial around until a stationary stop is reached. It has been noticed that in cases when the two digit numbers are the same, the user is liable to leave his finger in the selected finger hold and force the dial back to its normal position, thereby artificially increasing the speed of 20 rotation of the impulse wheel. The result may be that the impulses are not sent out in proper intervals for the control of the automatic switches.

Many inventors have sought to provide 30 means for preventing improper actuation of the dial during the sending out of impulses, by providing various kinds of locking means. The great drawback of such senders is that their cost is high and that they easily 35 get out of order.

The object of this invention is to provide a sender in which the possibility of the subscriber's interference with the sending out of impulses is reduced to a minimum.

According to the main feature of this invention means are provided for allowing the user's finger to slide out of engagement with the selected finger hold when the dial has 40 been moved to any of its operating positions.

The drawing represents a perspective 45 view of a calling device of the finger-hold dial type embodying this invention.

As calling devices of this class are well-known in the art, and since, in connection 50 with the present invention, the construction of the interior mechanism of the device is immaterial, in the following detail description only those parts of the apparatus will be described to which the invention is directed.

A manually rotatable setting member or dial 2 is provided with a plurality of finger-holds 3 around its periphery. The spaces between finger-holds 3 are open outwardly. In order to prevent the finger from sliding 60 out of engagement with a selected finger-hold 3, dial 2 is surrounded by a guiding member or frame 4. The different digit characters are provided on a plate 5 mounted below dial 2. Plate 5 may be either stationary or rotatable with dial 2. Instead of providing the digit characters on a separate plate, they may be printed on the dial 2 adjacent to the finger holds.

The user desiring to send out impulses 70 representing any digit, inserts his finger in the hold corresponding to that digit and rotates dial 2 until a stationary stop 6 provided on frame 4 is reached. During the forward rotation of dial 2, frame 4 prevents the user's finger from sliding out of the selected hold 3 in an outward direction. Adjacent to stop 6, however, a portion of frame 4 is cut away as shown, at 7, and when stop 6 is reached the user's finger will slide out of 80 the selected hold through this opening 7. In order to facilitate the sliding out of the operator's finger the stop 6 is inclined toward the opening 7 from the direction of approach of the finger holds, as shown in the 85 drawing. The dial is then free to return to normal without interference by the user and the impulse sending mechanism will send out the desired impulses in the proper manner.

While the setting member of the calling device is referred to as a dial, it will be obvious to those skilled in the art that this invention is not limited to the specified form of manually operable setting member shown, 90 but is equally well applicable to setting members of widely varying characters known in the art.

What is claimed is:

1. In a calling device, a manually operable member having finger holds, a stop toward which said finger holds move in the setting operation, and guiding means co-operating with said finger holds and having an opening adjacent to said stop. 100

2. A calling device comprising a movable member, provided with finger holds, a guide member co-operating with the finger holds and having an opening, and a stop situated adjacent to the opening in the guide member 110

and in the path of the finger holds, said stop being inclined toward the opening from the direction of approach of the finger-holds.

3. In a calling device, a manually operable member rotatable in a forward and backward direction having finger holds, a stop toward which said finger holds move in the setting operation, and guiding means

surrounding said finger holds and having an opening adjacent to said stop.

In witness whereof, I hereunto subscribe my name this 9th day of March A. D., 1915.

JAMES L. McQUARRIE.
